GUARD DEVICE FOR PAPER OR LIKE MACHINES

Louis Boraks, Brighton, Mass., assignor to Liberty Mutual Insurance Company, Boston, Mass., a corporation of Massachusetts

Application January 14, 1942, Serial No. 426,671

24 Claims. (Cl. 192—133)

My present invention relates to safety devices for paper cutting or like machines having a bed, a reciprocable blade, and mechanism adapted when actuated by the operator, to carry the blade out of and into an inoperative position thereby effecting a cutting stroke.

Such machines are efficient, but their operation is inherently dangerous and my present invention, resulting from an analysis of many accident cases, provides practical safeguards against the several causes of accidents revealed thereby to minimize the risks attendant their operation.

In accordance with my invention, I provide a paper or like cutting machine with a guard movable into or out of a position blocking access by the operator to the path of the blade, a lock to prevent actuation by the operator of the blade reciprocating mechanism, and means to release the lock when the guard is in blocking position.

In order to prevent the guard from being raised from its blocking position, after the cutting stroke has been initiated, I provide a lock, operable by the blade reciprocating mechanism, to hold the guard in its blocking position until the cutting stroke is completed.

While failure of the blade reciprocating mechanism to maintain the blade in its inoperative position until it is actuated is infrequent, I have provided a blade lock released or engaged by the guard as it is moved into or out of blocking position.

In practice, the lock holding the blade reciprocating mechanism against actuation is electrically operated and the control circuit includes a plurality of switches arranged in series therein. In accordance with my invention, the guard consists of a support, a plurality of fingers slidably carried by the support and a plurality of rods slidably carried by the fingers. Each rod and each finger carries a contact establishing one of the switches normally held open by gravity but closed as the guard is lowered to bring the rods into contact with the bed or objects supported thereon to effect relative movement between the fingers and the rods. Since the fingers and the rods are supported in telescoping relation to each other and to the support, the rods are movable as a unit relative to the support after each switch is closed, thereby permitting the guard to come into its blocking position against the bed regardless of objects supported thereon.

My invention includes many other novel features and has many advantages which will be apparent from the accompanying drawings and specification in which I have shown and de-

scribed my invention as embodied in a typical paper cutting machine, but which may be adapted to other machines without interference with their utility where accident experience indicates a need for safeguards that will protect the operator.

In the drawings:

Fig. 1 is a front view of a typical machine safeguarded in accordance with my invention.

Fig. 2 shows the machine of Fig. 1 in side view.

Fig. 3 is a fragmentary enlarged sectional view of the machine.

Figs. 4, 5 and 6 are fragmentary partly sectioned views of the guard structure.

Fig. 7 is a fragmentary view showing part of the blade reciprocating means in accordance with my invention.

Fig. 8 shows schematically an operating circuit.

Fig. 9 shows the lock preventing actuation of the blade reciprocating means, and

Fig. 10 shows the lock of Fig. 9 released.

I have shown my invention as incorporated in a typical paper cutting machine having a base 1, a bed 2, and sides 3 supporting a head 4. In such machines, the blade generally indicated at 5 is connected to the head 4 by links 6 permitting the blade 5 to be vertically reciprocated in the slideways 7 defined by the sides 3 (see Fig. 2).

As my invention is not concerned with the blade reciprocating means, these are not shown in complete detail. As shown in Fig. 1, the blade 5 is pivotally connected at one end to the blade carrier housing 8 by a link 9 and to the crank 10 on the shaft 11 by the connecting rod 12. I lock the crank 10 to the shaft 11 with a shear pin 13 (see Fig. 7).

The drive for the shaft 11 consists of a motor 14 having a belted connection with a pulley 15 mounted on the shaft 16 for rotation independently thereof but adapted to be coupled thereto by a clutch moved into and out of engagement by the manually operable lever 17 on the clutch operating shaft 18 journalled in the base 1. To simplify the drawings, I have not shown the clutch, the brake which holds the shaft 16 against rotation when the clutch is disengaged, or the gearing between the shafts 16 and 11. While I have not shown the blade reciprocating means in detail, it will be understood that machines of the type illustrated conventionally provide for the reciprocation of the blade 5 out of and into an inoperative position remote from the bed 2 to effect a complete cutting stroke

55

when the lever 17 is moved into and out of its full line position as shown in Fig. 1.

The bed 2 slidably supports a stock gage 19 in a slot 20. The gage 19 is attached to a chain 21 supported on sprockets 22 and 23 moved in the slot 20 towards or away from the path of the blade 5 by the hand wheel 24 in control of the sprocket 22, and carries a post 25 connected to a tape 26 guided on sheave wheels 27 and 28 to permit the gage 19 to be easily and accurately positioned.

Conventional paper cutting machines also include a press 29 guided in slideways 30 in the sides 3 of the machine. The press 29 has a threaded aperture 31 to receive the screw 32 supported in the head 4 for rotation with the hand wheel 33 whereby the press 29 may be fed down to engage and hold a stack S of paper or the like in position on the bed 2 against the gage 19 (see Fig. 3).

In accordance with my invention, I provide the cutting machine with a guard generally indicated at G adapted to be moved into and out of a position blocking access by the operator to the path of the blade 5. In the embodiment of my invention shown in the drawings, the guard G consists of a support 34 carrying supporting wheels 35 and having its bottom wall formed with a plurality of spaced apertures in which I position seats 36. The support 34 presents a chamber C.

In order to slidably support the guard G, I attach plates 37 to each of the sides 3 of the machine. Each of the plates 37 carries a track or guideway 38 for the wheels 35. Preferably the tracks 38 are pivotally attached as at 39 at their upper ends to the plates 37 and each includes an arm 40 extending through a guide 41 on the lower end of each of the plates 37. The arms 40 are under the influence of springs 42 resiliently urging the tracks 38 against stops 43 on the plates 37 (see Fig. 3).

While the guard may be moved into and out of its blocking position by any suitable means, I provide the plates 37 with rearwardly disposed arms 44 to which the frame 45 is pivotally supported as by the rod 46. The frame 45 is counterweighted as at 47 and is interconnected at its front end by a rod 48 presenting a readily accessible handle for engagement by the operator.

The guard support 34 carries arms 49 connected to the frame 45 by links 53 intermediate the handle 48 and the pivot 46.

The guard G includes a plurality of fingers 51 the construction and function of which may be most readily appreciated from a consideration of Figs. 1, 4, 5 and 6. The fingers 51 are tubular and are threaded at their upper ends to receive heads 52 formed to present an external shoulder engageable with the seats 36, which are preferably provided with a resilient cushion 53, in order that the fingers 51 may be slidably supported to permit relative movement between the support 34 and the fingers 51, thereby providing a barrier that adapts itself to any objects supported on the bed 2. The heads 52 are also formed to present an internal shoulder to be engaged by the heads 54 attached to rods 55 so that the rods 55 may be slidably supported within the fingers 51. The rods 55 are of sufficient length to protrude from the lower ends of the fingers 51. By this construction, I provide a guard in which the rods 55 and the fingers

51 are supported in telescoping relation to each other and to the support 34.

In accordance with my invention, I provide means to prevent actuation by the operator of the blade reciprocating mechanism until he has brought the guard G into a position blocking access to the path of the blade 5.

I accomplish this result by providing a circuit 56 including a plurality of switches arranged therein in series. The switches may each conveniently comprise a pair of contacts 57 and 58 with the contacts 57 being carried by caps 59 attached to the heads 52 and the contacts 58 being attached to the heads 54. The contacts 57 and 58 are spaced apart by gravity, as shown in Fig. 4, when the guard G is remote from the bed 2, but are brought into mutual contact by movement of the fingers 51 relative to the rods 55 when the rods 55 strike the bed 2 or objects S supported thereon as shown in Fig. 5. In order to insulate the rods 55 and the fingers 51 from each other and from the support 34, the heads 52 and 54 are of suitable non-conductive stock.

The heads 52 are slotted as at 52' to accommodate the wire connecting a contact 58 of one switch to the contact 57 of the next adjacent switch. By this construction, the circuit is maintained open until each rod 55 has contacted the bed 2 or objects supported thereon and relative movement effected between the fingers 51 and the rods 55 to bring the contacts 57 and 58 into mutual contact.

As shown in Fig. 6, the fingers 51 and the rods 55 are movable as a unit relative to the support 34 to permit the guard to be moved into a position wherein the remaining switches are closed. In Fig. 1, I have shown the guard in a position wherein certain switches are closed by engagement with the stock S, but further movement of the guard is necessary to effect the closing of the remainder of the switches.

At 60, I have indicated a slideway mounted on the base 1 (see Figs. 1, 9 and 10) supporting a slide 61 connected by a link 62 to an arm 63 movable with the lever 17. The slideway 60 and the slide 61 have apertures 64 and 65, respectively, in registry when the lever 17 is in its inoperative position, thereby to receive a locking pin 66 under the influence of gravity to prevent movement of the lever 17 by the operator. The locking pin 66 is withdrawn from its locking position when the solenoid 67 is energized.

As shown in Fig. 8, I provide an electric circuit 69 having a switch 70 and a transformer 71 in series and a normally open relay 72, the solenoid 67 and a signal light 74 in parallel with the transformer 71. The circuit 56 includes the transformer 71, the switches defined by the pairs of contacts 57, 58 and the relay 72. This circuit has the advantage of permitting the circuit 56 to control the solenoid 67 with the current in the circuit 56 being of reduced voltage.

I also provide means operable by the blade reciprocating mechanism for locking the guard G in its blocking position after the cutting stroke has been initiated by the operator and maintaining it locked in that position until the cutting stroke is completed. This is particularly desirable where the guard positioned means are counterweighted to effect its return to an inoperative position by gravity.

I accomplish this result by providing a latch 74 pivotally supported on one side 3. The latch 74

is adapted to engage the frame 45 but is normally maintained in an inoperative position by gravity. To actuate the latch 14, I employ a lever 75 pivotally mounted as at 76 and normally urged into an inoperative position by the spring 77. I attach to the arm 63 a thrust arm 78 to carry the lever 75 into a position to rock the latch 14 into engagement with the frame 45 thereby locking the guard G in blocking position until the cutting stroke is completed.

While the guard lock 74 may be actuated as desired by the blade reciprocating mechanism, the actuating means disclosed has one practical advantage. I mount on one end of the blade 5 a block 79 under which the upper end of the lever 75 is adapted to pass under the influence of the spring 77. In the event that the brake for the shaft 16 should start to fail, for example, or for any other reason indicative of the need of service the blade 5 should fail to return to its inoperative position, the failure of the upper end of the lever 75 to pass under the block 79 would be apparent to the operator and signal to him the immediate need of repair.

While accident experience demonstrates that the great majority of accidents are due to the fault of the individual, there is the possibility of failure of some part of the operating mechanism in any machine. Accordingly, I have provided means to lock the blade 5 in its inoperative position wherein the guard G is positioned to permit access by the operator to the path of the blade 5. To accomplish this result, I provide the head 4 with a pair of hooks 80 pivotally supported on mounts 81 to engage with pins 82 carried by the blade 5 (see Fig. 1). I interconnect the hooks 80 with a link 83 which supports a cam track 84 to receive a pin 85 carried by the support 34 of the guard G. The cam track 84 is shaped so that as the guard G is lowered, the hooks 80 are pivoted into a position free of the pins 82 to permit the blade 5 to be lowered. The provision of such blade locking means makes necessary the use of the shear pin 13 connecting the crank 10 to the shaft 11, although the use of a shear pin is of decided advantage apart from this feature of my invention.

The mounts 81 also carry stops 86 to limit the upward movement of the guard G.

From the foregoing it will be apparent that in order for machines incorporating my invention to be operated, the operator must bring the guard G into its blocking position and hold it in that position until he has brought the lever 17 into a position wherein the clutch is engaged. Movement of the guard G from its position remote from the bed 2 to its blocking position, unlocks the blade 5 from the head 4 and closes the circuit 56 to the relay 72 thereby effecting the energization of the solenoid 67. The solenoid 67 withdraws the pin 66 from its position locking the slide 61 in the slideway 68 permitting the lever 11 to be moved by the operator. Actuation of the lever 17 results in the latch 14 engaging with the frame 45 to hold the guard G in blocking position until the lever 17 is returned to a position wherein the clutch is disengaged.

When the lever 17 is returned to its inoperative position, the guard G may be raised to permit access by the operator to the path of the blade 5 and as the guard G is raised the circuit 56 is opened and the blade 5 is locked to the head 4.

My invention, therefore, provides means for practically safeguarding paper cutting or like ma-

chines, the operation of which is inherently dangerous, and may be attached to any machine of the type under consideration to provide any one or more of the practical inexpensive safeguards contemplated by it against the several causes of accidents resulting from the operation of such machines without interference with their utility.

What I therefore claim and desire to secure by Letters Patent is:

10. 1. Safety mechanism for paper cutting or like devices having a bed, a reciprocable blade, and means engageable by one hand of the operator to reciprocate said blade out of and into an inoperative position to effect a cutting stroke, said safety mechanism comprising a guard engageable by the other hand of the operator and slidably supported on said device to be positioned to block access by the operator to the path of said blade or to permit such access, means to lock said blade reciprocating means against actuation, and means operable to release said locking means when said guard is in blocking position.
15. 2. Safety mechanism for paper cutting devices or the like having a bed, a reciprocable blade, and means to reciprocate said blade out of and into an inoperative position to effect a cutting stroke, said safety mechanism comprising a guard slidably supported in said device to be movable by the operator from a position permitting access by the operator to the path of said blade to a position blocking such access, means to lock said blade reciprocating means against actuation, means operable to release the locking means when said guard is in blocking position, and means locking said guard in blocking position until said cutting stroke is completed.
20. 3. Safety mechanism for paper cutting devices or the like having a bed, a reciprocable blade, and means to reciprocate said blade out of and into an inoperative position to effect a cutting stroke, said safety mechanism comprising a guard slidably supported in said device to be movable by the operator from a position permitting access by the operator to the path of said blade to a position blocking such access, means carried by the device to lock said blade in its inoperative position, and means carried by said guard to unlock said blade locking means when said guard is in its blocking position.
25. 4. The safety mechanism of claim 3 in which the blade locking means include interconnected blade engaging hooks and a cam track and the guard carries a track engaging member.
30. 5. The safety mechanism of claim 3 in which the blade reciprocating means includes a drive shaft, an eccentric mounted thereon, and a shear pin anchoring the eccentric to the shaft.
35. 6. Safety mechanism for paper cutting devices or the like having a bed, a reciprocable blade, and means to reciprocate said blade out of and into an inoperative position to effect a cutting stroke, said safety mechanism comprising a guard slidably supported in said device to be movable by the operator from a position permitting access by the operator to the path of said blade to a position blocking such access, means carried by the device to lock said blade in its inoperative position to said device, means carried by said guard to unlock said blade locking means when said guard is in its blocking position, means to lock the blade reciprocating means against actuation, means to release the last named lock when the guard is in blocking position, and means locking the guard in blocking position until the cutting stroke is completed.
40. 7. The safety mechanism of claim 6 in which the blade locking means include interconnected blade engaging hooks and a cam track and the guard carries a track engaging member.
45. 8. The safety mechanism of claim 6 in which the blade reciprocating means includes a drive shaft, an eccentric mounted thereon, and a shear pin anchoring the eccentric to the shaft.
50. 9. The safety mechanism of claim 6 in which the blade locking means include interconnected blade engaging hooks and a cam track and the guard carries a track engaging member.
55. 10. The safety mechanism of claim 6 in which the blade reciprocating means includes a drive shaft, an eccentric mounted thereon, and a shear pin anchoring the eccentric to the shaft.
60. 11. The safety mechanism of claim 6 in which the blade locking means include interconnected blade engaging hooks and a cam track and the guard carries a track engaging member.
65. 12. The safety mechanism of claim 6 in which the blade reciprocating means includes a drive shaft, an eccentric mounted thereon, and a shear pin anchoring the eccentric to the shaft.
70. 13. The safety mechanism of claim 6 in which the blade locking means include interconnected blade engaging hooks and a cam track and the guard carries a track engaging member.
75. 14. The safety mechanism of claim 6 in which the blade reciprocating means includes a drive shaft, an eccentric mounted thereon, and a shear pin anchoring the eccentric to the shaft.

7. Safety mechanism for paper cutting or like devices having a bed, a reciprocable blade and manually operable means to reciprocate said blade out of and into an inoperative position to effect a cutting stroke, said safety mechanism comprising a guard slidably supported in said device to be movable by the operator from a position permitting access by the operator to the path of said blade to a position blocking such access, and means operated by the blade reciprocating means to lock said guard in blocking position until the cutting stroke is completed.

8. Safety mechanism for paper cutting or like devices having a bed, a reciprocable blade and means to reciprocate said blade out of and into an inoperative position to effect a cutting stroke, said safety mechanism comprising a guard slidably supported in said device to be movable by the operator from a position permitting access by the operator to the path of said blade to a position blocking such access, means operated by said guard to lock said blade in its inoperative position to said device when said guard is positioned to permit access to its path, and means operated by the blade reciprocating means to lock said guard in blocking position until the cutting stroke is completed.

9. Safety mechanism for paper cutting or like devices having a bed, a reciprocable blade and means to reciprocate said blade out of and into an inoperative position to effect a cutting stroke, said safety mechanism comprising a guard slidably supported in said device to be movable by the operator from a position permitting access by the operator to the path of said blade to a position blocking such access, independent means to lock said blade reciprocating means against actuation, means operable to release said blade locking means when said guard is in blocking position, and means operated by the blade reciprocating means to lock said guard in blocking position until the cutting stroke is completed.

10. Safety mechanism for paper cutting or like devices having a bed, a vertically reciprocable blade, means to reciprocate said blade out of and into an operative position to effect a cutting stroke, and a manually operable control to actuate said blade reciprocating means, said safety mechanism comprising a guard member, means slidably supporting said guard member for vertical movement into and out of a position blocking access by the operator to the path of said blade, a plurality of guard fingers supported by said guard member to permit relative vertical movement between said guard member and said guard fingers, a contact carried by each of said guard fingers to permit relative vertical movement between said contacts and said guard fingers, means to lock said manually operable control against actuation, electrically operable means to release said locking means, and an electric circuit in control of said electrically operable means, a plurality of switches arranged in series in said circuit, each of said switches being normally open and closed by relative movement between said contacts and said guard fingers.

11. The safety mechanism of claim 10 in which the means to lock the manually operable control against actuation comprises a slide carried by the manually operable control, a guide carried by the device to slidably receive the slide, the guide and the slide each having apertures in registry with each other when the manually operable control is in its inoperative position, and a locking pin carried by the electrically operable means entrant

of said aperture when in registry with each other under the influence of gravity and retracted therefrom when the electrically operable means are energized.

12. The safety mechanism of claim 10 in which the electric circuit includes a first parallel circuit to the electrically operable means, a second parallel circuit including a transformer, the switches and a relay in control of the first parallel circuit.

13. Safety mechanism for paper cutting devices or the like having a bed, a vertically reciprocable blade, means to reciprocate said blade out of and into an inoperative position to effect a cutting stroke, and a manually operable control to actuate said blade reciprocating means, said safety mechanism comprising a guard, means attached to the device slidably supporting said guard to permit it to be positioned to block access by the operator to the path of the blade or to permit such access, manually operable guard positioning means, pivotally supported by said device and pivotally connected to said guard, said guard positioning means being counterweighted to urge said guard away from its blocking position, a latch to lock said guard positioning means, and means to move said latch into and out of locking position at the start and finish of the cutting stroke.

14. Safety mechanism for paper cutting devices or the like having a bed, a vertically reciprocable blade, means to reciprocate said blade out of and into an inoperative position to effect a cutting stroke, and a manually operable control to actuate said blade reciprocating means, said safety mechanism comprising a guard, means attached to the device slidably supporting said guard to permit it to be positioned to block access by the operator to the path of the blade or to permit such access, manually operable guard positioning means pivotally supported by said guard supporting means, a latch to lock said guard positioning means when said guard is in blocking position, and means actuated by said manually operable control to hold said latch in its operative position until the cutting stroke is completed.

15. The safety mechanism of claim 14, the means slidably supporting the guard comprising a member attached to the device on opposite sides of the bed, a vertical guide carried by each member, and anti-friction elements carried by the guard to engage with the guides.

16. The safety mechanism of claim 14, the means slidably supporting the guard comprising a member attached to the device on opposite sides of the bed, a vertical guide for the guard pivotally attached to each member, means resiliently urging each guide towards the path of the blade, a stop carried by each member to limit the movement of each guide when under the influence of the resilient means.

17. Safety mechanism for paper cutting or like devices having a bed, a vertically reciprocable blade, and means to reciprocate said blade out of and into an operative position to effect a cutting stroke, said safety mechanism comprising a guard member, means slidably supporting said guard member for vertical movement into and out of a position blocking access by the operator to the path of said blade, a plurality of depending tubular fingers slidably supported by said guard member to permit relative vertical movement between said guard member and said fingers, a rod slidably supported within each of said fingers with its bottom end protruding there-

from, means to lock said reciprocating means against actuation, and electrically operated means to release said locking means, said electrically operated means including a circuit, a plurality of switches arranged in series in said circuit, said switches comprising contacts carried by said fingers and contacts carried by said rods for mutual engagement on predetermined relative movement between said rods and said fingers when said rods engage said bed or objects supported thereon as said guard is moved into said blocking position, said contacts being disengaged by gravity as said guard is moved away from said blocking position.

18. The safety mechanism of claim 17 in which the fingers and the rods include heads, the heads of the fingers present external and internal shoulders engageable with the guard member and by the rod heads respectively to effect the support of the fingers and rods in telescoping relation to the guard member and to each other.

19. The safety mechanism of claim 17 in which the fingers and the rods include heads, the guard member is formed with a plurality of spaced apertures slidably receiving the fingers and carries resilient seats for the finger heads, the finger heads present a seat for the rod heads, one of the switches establishing contacts is carried by each of the heads, and the heads are of insulating material to insulate the contacts from each other and from the rods and the fingers.

20. Safety mechanism for paper cutting or like devices having a bed, a vertically reciprocable work element and means to reciprocate said element out of and into an inoperative position to effect a work stroke, a normally inoperative control for said reciprocating means, said control including manually operable means and electrically operated means, said control being inoperative until both of its means are actuated, a guard slidably supported by said device for vertical movement by the operator into and out of a position blocking access by the operator to the path of said element, an electric circuit, said circuit including said electrically operable means and a plurality of switches carried by said guard, each of said switches including a member slideable with reference to said guard and operable to open it under the influence of gravity and to close it when it strikes said bed or an object supported thereon and is moved relative to said guard as said guard is moved into blocking position whereby the operation of said device is dependent on the movement of said guard by the

operator into blocking position to close said switches and actuation of said manually operable control means.

21. The mechanism of claim 20 and a latch carried by the device and operable to hold the guard in blocking position when the manually operable means is actuated.

22. The mechanism of claim 20 and a lock for the element carried by the device and means carried by the guard to unlock and lock the lock as the guard is moved into and out of its blocking position.

23. In safety mechanism for paper cutting or like devices having a bed, a vertically reciprocable work element and means to reciprocate said element out of and into an inoperative position to effect a work stroke, a guard slidably supported by said device for vertical movement by the operator into and out of a position blocking access by the operator to the path of said element, and a plurality of fingers slidably supported by said guard for vertical movement relative thereto to establish a barrier conformable to said bed and objects supported thereon.

24. Safety mechanism for paper cutting or like devices having a bed, a vertically reciprocable work element and means to reciprocate said element out of and into an inoperative position to effect a work stroke, electrically actuated means in control of said reciprocating means, a guard slidably supported by said device for vertical movement by the operator into and out of a position blocking access by the operator to the path of said element, a plurality of fingers slidably supported by said guard for vertical movement relative thereto to establish a barrier conformable to said bed and objects supported thereon, a contact carried by each of said fingers to permit relative vertical movement between said contacts and said guard fingers, a second contact carried by each of said fingers, said contacts establishing switches normally held open by the influence of gravity on said first named contacts but adapted to be closed when said guard is positioned to bring said fingers into contact with said bed and to cause relative movement between said fingers and said first named contacts, an electric circuit including said switches and said electrically actuated means whereby the operation of said device is dependent on the movement of said guard by the operator into blocking position.

LOUIS BORAKS.
